UNITED STATES PATENT OFFICE.

ARTHUR W. SMITH, OF NEW YORK, N. Y., ASSIGNEE TO REMINGTON TYPEWRITER COMPANY, OF ILLION, NEW YORK, A CORPORATION OF NEW YORK.

TYPE-WRITING MACHINE.

1,126,895.

Specification of Letters Patent.

Patented Feb. 2, 1915.

Application filed June 28, 1913. Serial No. 773,848.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10. My invention relates to typewriting machines and more particularly to the paper feed mechanism of such machines.

My invention has for its principal object to provide for a typewriter or other machine having a roller platen, paper feed devices which are simple and inexpensive to manufacture but are thoroughly good and efficient in use.

To the above and other ends my invention 20 consists in certain features of construction and combinations and arrangements of parts, all of which will be fully set forth herein and particularly pointed out in the claims.

25. In the accompanying drawings, Figure 1 is a fore and aft vertical sectional view of the carriage of a typewriting machine having my invention embodied therein and showing the parts in normal position. Fig. 2 is a fragmentary or diagrammatic view like a part of Fig. 1 and showing the main feed roller in released position. Fig. 3 is a view like Fig. 2, but showing the paper apron and paper finger devices in paper releasing position. It will be seen that Figs. 2 and 3 together show the paper feed mechanism in releasing position. Fig. 4 is a rear elevation. Fig. 5 is a fragmentary front elevation of parts of the mechanism.

40. In all of the views some of the mechanism of a typewriter carriage is omitted. Other parts of a typewriting machine of which the carriage shown in the present case is adapted to constitute a part, are 45 shown in other pending applications of mine. It will be understood, however, that the paper feed mechanism, either in its entirety or, as to some of its features, is applicable or adaptable to other typewriting

50. machines and also to other printing machines, such for example as some forms of adding machines.

The carriage shown in the drawings comprises a main transverse bar 1 having the 55 form of a rail with grooves 2 in its front

and rear edges, which grooves are adapted to coöperate with ball or roller bearings and with stationary grooved rails to enable the carriage to travel back and forth across the machine in the manner well known in the art. Secured to each end of the bar 1 is an end piece or bracket 3, the form of which can for the present purposes be sufficiently well understood from the drawings and in which is journaled the axle 4 of a 65 roller platen 5. Any suitable means can be provided for turning said platen which, in the present instance, is shown equipped with one or more finger wheels 6 and also with a ratchet or line space wheel 7, the latter 70 for coöperation with other line feed devices not herein shown.

The paper feed mechanism is mounted in part on a transverse frame rod 8 which at its ends is rigidly secured in the brackets 3 75 behind the platen.

A main feed roller 10 has an axle 11, the ends of which are journaled in the free ends of arms 12, which arms are pivoted on the rod 8. Each of the arms 12 forms part of 80 a lever of the first order, which lever also has an upwardly extending arm 13, on which acts a contractile spring 14, which spring is connected at its rear end to a bracket or arm 15 rigidly mounted on and projecting 85 toward the rear from a collar 16, which collar is mounted on the rod 8 and secured in position by a set screw 17. Said collar 16 is shouldered in order to secure the arm 15 thereto and it has a reduced part that projects toward the middle of the machine beyond said arm 15 and into position to prevent motion of the levers 12, 13 toward the end of the carriage. In order to regulate the tension of the spring 14, said spring has 90 a nut inserted therein and into said nut is threaded an adjusting screw 18 that passes loosely through a hole in the arm 13. It will be seen that the tension of the spring 14 normally presses the roller 10 against the 100 platen.

The feed roller 10 and the means for mounting the same and for pressing it against the platen, all as shown and described above, are of ordinary construction 105 and no claim is made herein for these devices by themselves; and in fact some other specific construction can be substituted for them if preferred.

I have provided a paper apron or de- 110

5 flector 20 lying beneath the platen and curved into a sort of general conformity to the curvature of the platen as shown in Figs. 1 and 3. This paper apron or deflector is supported for bodily motion in a general fore and aft direction and suitable means are provided for guiding this motion of the forward part of said paper apron in a general front and back direction but preferably 10 in a direction forward and more or less inclined downward and back at a corresponding inclination upward so that when the paper apron is drawn toward the rear its forward part moves rearward and more or less upward and is pressed against the surface of the platen at a suitable distance below the writing line, as will be understood by reference to Fig. 1. This guiding means can, for some of the purposes of my invention, be of any suitable specific construction. 15 In the present instance the extreme forward part of the paper apron is prolonged to the brackets or end pieces 3 where it is formed with ears 21 bent off at right angles, and 20 approximately contacting with the inner surfaces of said brackets. As best shown in Fig. 3, each of these ears is formed with an elongated slot 22, which slot extends in a direction forward at a downward inclination 25 and backward at an upward inclination and in which is a rod 23 supported by the end bracket 3 so that said rod and said slot guide the forward part of the paper apron in the manner which has been described. 30 The rear edge of the paper apron 20 falls a little short of reaching to the main feed roller 10 throughout the greater part of the length of said paper apron but at its ends said apron is formed with prolongations 24, 35 best shown in Figs. 3 and 4, and each of said prolongations has an ear 25 bent off therefrom. A contractile spring 26 is connected to each of the ears 25 and the rear end of said spring is connected with an arm 27 40 rigidly mounted on the rod 8 to which it is secured by a set screw 28. It will be perceived that the springs 26 exert their tension on the paper apron in a direction that is substantially a direct rearward pull. In the 45 present instance and preferably the springs 26 constitute the sole support for the rear part of the paper apron. It will be seen that this leaves said paper apron free to be depressed at its rear part for the insertion 50 of a thick bunch of papers.

55 The paper feed release mechanism comprises a handle 30 consisting of a lever arm rigidly mounted on a rock shaft 31 which at its ends is suitably pivoted in the brackets 60 3 and which passes across the carriage just above the roller 10 and in front of the arms 12. In the present instance the handle or lever arm 30 consists of a strip of sheet metal so bent as to pass under the rod 8 and 65 thence upward into position for convenient

manipulation. The rock shaft 31 normally occupies the position shown in Fig. 1 and it is operated to release the paper by pushing the lever arm 30 back to the position shown in Figs. 2 and 3. Said rock shaft has thereon two sets of releasing arms, namely, arms or pins 32, Fig. 2, for coöperation with the arms 12 and also arms or pins 33, Fig. 3, for coöperation with the paper apron 20. The arms 32 lie just in front of the arms 12 so 70 that when the handle 30 is operated said arms 32 depress said arms 12 against the tension of the springs 14 and release the feed roller 10, as shown in Fig. 2. The arms 33 occupy the positions shown in Figs. 80 3 and 4 where it will be seen that they extend down behind the extreme rear edge of the rearwardly projecting parts 24 of the paper apron. The construction is such that when the handle 30 is operated as shown in Fig. 3 these arms move toward the front of the machine and push the paper apron bodily toward the front. Its motion is guided by the slots 22 and rods 23 so as to move the forward part of the paper apron 90 away from the platen as shown in Fig. 3. It will of course be understood that other means can be provided for moving the paper apron bodily toward the front.

95 I provide a pair of marginal guiding devices for coöperation with the margins of the paper at and above the writing line, and means for controlling said guiding devices. Each of said guiding devices comprises a feed roller 34 having trunnions 35 journaled 100 in the forked upper end of an arm or paper finger or paper guide 36, said finger or guide consisting of a strip of sheet metal which at its lower end is widened out and folded approximately into a square tube as shown 105 in Figs. 1 and 5 at 37, and each of said sheet metal arms has also formed as part thereof a forwardly projecting finger piece 38. The square barrel, hub or sleeve 37 fits on a square shaft, which shaft in the present instance consists of the rod 23 that serves also as a guide for the ears 21 of the paper apron. There are two of these rods or shafts 23 and they are arranged end to end, their inner 110 ends being cylindrical and of reduced diameter, as shown in Figs. 1 and 5, and journaled in a sheet metal bracket 40 secured to the paper apron 20 at about the middle thereof. Each of these shafts 23 is journaled 115 in and passes through one of the end pieces 120 or brackets 3 and on the outer end of each shaft there is rigidly mounted an arm 41 constituting a finger piece for turning the shaft; and said arm also has connected thereto a spring 42 the rear end of which is connected to a pin 43 projecting from the bracket 3. This spring exerts its tension to turn the shaft 23 in such a direction as to cause the roller 34 to press against the front face of the platen; and by pulling forward 125 130

- on the arm or finger piece 41 this spring tension can be relieved, and the paper finger or margin guide can then be adjusted longitudinally of the rod 23 with ease.
- 5 The arm 41, spring 42, shaft 23 and the paper guiding and feeding devices 36 and 34 are all similar in details of construction to the corresponding parts now in use on the Remington typewriter. I therefore do not
- 10 claim anything new in the specific construction of these parts, and as far as some of the features of my invention are concerned, they may be constructed otherwise than as shown. I do, however, claim the co-operation
- 15 of said parts with the paper apron 20 in the respects that said shafts are associated with said paper apron at the outer ends thereof and also that said shafts are connected to and supported by the paper apron
- 20 at the middle of the machine and also, as will presently be described more in detail, in the respect that the marginal guide devices and the rod or rods on which they are mounted are moved toward and from the
- 25 platen by and in unison with the paper apron, in one instance to cause the parts to co-operate with the paper and in the other instance to cause said parts to release the paper.
- 30 It will be noted in Fig. 1 that the arm 36 lies just in front of the front edge of the paper apron 20 and when said paper apron is moved toward the front of the machine as in Fig. 3, this arm is also moved toward
- 35 the front of the machine, releasing the pressure of the roller 34 on the paper. It will be noted that when the marginal guide devices are adjusted near the ends of the platen, that the rods 23 on which they are
- 40 mounted partake in but a slight degree of the motion of the paper apron in the releasing operation. When the marginal paper guides are thus adjusted there is but little flexure of the rods 23 due to the pressure
- 45 on said devices because the devices are then near the fixed pivots of the rods. When, however, said devices are adjusted near the middle of the platen to co-operate with a card or narrow piece of paper, then the rods themselves move outward with the paper apron. In either case both the marginal guides and the rods on which they are supported move with the paper apron in the releasing operation and said marginal guides are themselves moved to releasing
- 50 position by said paper apron.
- 55 I provide a paper table 44 at the rear side of the platen, said paper table consisting of a plate of sheet metal of suitable form having riveted to the rear face thereof two knuckles 45, each constituting one member of a hinge. The members 45 consist each of a strip of sheet metal having its lower end rolled into a cylinder 46 into which projects
- 60 a pin 47 constituting the other member of
- the hinge. Said pin 47 is part of a sheet metal bracket stamped out as a blank and folded or bent into the form shown in the drawing. Said blank is formed with two branches or arms 48 which are bent back into parallelism and in planes at right angles to the arms 47 and perforated and placed upon the rod 8. The arms or ears 48 are connected by a yoke part through which is threaded a set screw 50, which screw at its inner end engages a flattened part 51 of the rod 8 so as to secure the entire bracket against either sliding or turning on said rod. Said bracket is also formed with another arm 52 which extends upward and rearward and serves as a prop or rest to support the upper part of the paper table and to limit the extent to which said paper table can turn about its hinges. Just above one or both of the arms 52 a lug or pin 53 projects toward the rear from the paper table and the parts are so adjusted that they have to be sprung a little in order to get the arm 52 caught under this lug 53. The result is that the upper end of the arm co-operating with the notch between the flat surface of the paper table and the lug 53, acts as a sort of detent to prevent accidental turning of the paper table toward the front of the machine. Said paper table can, however, be turned toward the front by the exertion of a little force to spring the arm out from the notch. It is desirable to have the paper table hinged in this way because there are some devices underneath it that may occasionally require attention. The paper table can be removed at any time by loosening one of the screws 50 and sliding the stationary hinge-member toward the middle of the machine, thus pulling the pin 47 out of the knuckle 45.
- 65 Various changes can be made in the details of construction and arrangement without departing from my invention.
- 70 What I claim as new and desire to secure by Letters Patent, is:—
- 75
1. In a typewriting machine, the combination of a platen, a paper apron, means for guiding the forward part of said paper apron back and toward the platen and forward and away from the platen, and spring means tending to move said paper apron toward the rear to press its forward part against the platen, said spring means acting on the rear part of said paper apron and constituting the sole support of said rear part.
- 80
2. In a typewriting machine, the combination of a platen, a paper apron, means for guiding the forward part of said paper apron back and toward the platen and forward and away from the platen, spring means tending to move said paper apron toward the rear to press its forward part against the platen, said spring means acting on the rear part of said paper apron and

- 2
- constituting the sole support of said rear part, and means for moving said paper apron toward the front against the tension of said spring means to release the paper.
- 5 3. In a typewriting machine, the combination of a platen, a paper apron mounted for motion toward and away from said platen, a marginal paper guide and a rod supported in part by said paper apron and 10 along which said marginal paper guide is adjustable.
4. In a typewriting machine, the combination of a platen, a paper apron or deflector, two rods, each supported at its inner end by said paper apron and independently supported at its outer end, and two marginal paper guides, one adjustable along each of said rods.
5. In a typewriting machine, the combination of a platen frame having end pieces, a platen journaled in said end pieces, a paper apron or deflector, two rods, each mounted at its outer end in one of said end pieces, and each mounted at its inner end on 25 said paper apron, and said paper apron at its ends supported by said rods.
6. In a typewriting machine, the combination of a platen frame having end pieces, a platen journaled in said end pieces, a paper apron or deflector, two rock shafts each journaled at its outer end in one of said end pieces, and each mounted at its inner end on said paper apron, and said paper apron at its ends supported by said rock 35 shafts, marginal paper guides connected with said rock shafts, and means for turning either of said rock shafts to move the corresponding paper guide away from the platen.
- 40 7. In a typewriting machine, the combination of a platen, a paper apron guided at its forward part for bodily motion in a front and back direction, and contractile springs, each connected with the rear part 45 of said paper apron and extending thence toward the rear of the machine and tending to move said paper apron bodily toward the rear.
8. In a typewriting machine, the combination of a platen, a paper apron guided at its forward part, contractile springs attached to the rear part of said apron and extending rearward therefrom to draw said paper apron toward the rear and against the platen, and a paper feed release device 55 including a rock shaft having arms adapted to press against the rear part of said paper apron and push it forward against the tension of said spring means.
9. In a typewriting machine, the combination of a platen, a paper apron, a rod disposed along the forward part of said paper apron, a marginal paper guide mounted on said rod and coöperating with the platen, and means for moving said marginal paper 60 guide and said paper apron together toward the front of the machine to release the paper.
10. In a typewriting machine, the combination of a platen, a paper apron, a rod disposed along the forward part of said paper 70 apron, a marginal paper guide mounted on said rod and coöperating with the platen, and means for moving said marginal paper guide, said rod and said paper apron together toward the front of the machine to 75 release the paper.
11. In a typewriting machine, the combination of a platen, a paper apron, a rod disposed along the forward part of said paper 80 apron, a marginal paper guide mounted on said rod and coöperating with the platen, means for moving said marginal paper guide and said paper apron together toward the front of the machine to release the 85 paper, and means whereby said rod guides the forward part of said paper apron forward and away from the platen and backward and toward the platen.

Signed in the borough of Manhattan, city 90 of New York, in the county of New York, and State of New York, this 27th day of June, A. D. 1913.
